ROBERT JOHN ALEXANDER CHANDLER, OF LONDON, ENGLAND, ASSIGNOR TO AMERICAN MACHINE & FOUNDRY COMPANY, A CORPORATION OF NEW JERSEY

CIGARETTE CUTOFF

Application filed February 14, 1930. Serial No. 428,475.

This invention relates to improvements in cigarette machine cutoffs, particularly to the type in which the cutoff blade is moved in an orbital path intercepting the path of the cigarette rod and at the same time following the rod.

The main object of the present invention is to provide a cutoff mechanism in which the cutoff blade and the ledger plate are carried by the same frame for movement in unison, thus avoiding the necessity for separate reciprocation of the ledger plate as has hitherto commonly been the practice. In this manner, the ledger plate is given the same smooth circular motion that the knife receives, thus eliminating one source of vibration. Moreover, the extra parts for reciprocating the ledger plate are dispensed with. Also when the ledger plate is separately reciprocated, while the knife is moved in an orbital path, there is a small but objectionable longitudinal differential movement between the ledger plate and the blade which varies the clearance between the ledger plate and knife and results in imperfect cuts. Another object of the invention is to provide simple and effective means for rotating the blade as it travels along its orbital path. Still another object of the invention is to provide a three point connection between the frame carrying the blade and ledger plate and the means supporting the frame for movement, in order to resist the tendency of the frame to sidesway about two points as an axis and to resist the torque resulting from driving the blade.

With these and other objects not specifically mentioned in view, the invention consists of certain constructions and combinations which will be hereinafter fully described and then specifically set forth in the claims hereunto appended.

In the accompany drawings; which form a part of this specification and in which like characters of reference indicate the same or like parts, Fig. 1 is a front elevation partly in section of a cutoff mechanism constructed in accordance with the invention; Fig. 2 is a detail view in front elevation and partly in section of the cutoff blade shown in Fig.

1, the full lines showing the blade in cutting position, and the dotted lines in the mid-position between cuts; Fig. 3 is a side elevation of the device shown in Fig. 1; Fig. 4 is a plan view of the device shown in Fig. 1.

In carrying the invention into effect there is provided a flying frame, a cutoff blade of the usual kind and a cooperating ledger plate both the cutoff blade and the cooperating ledger plate being carried by said frame for movement in unison therewith, and means for moving said frame in an orbital path to cause the blade and the ledger plate to operate on the rod. In the best constructions said means includes cranks supporting the frame. Preferably the frame supports the blade and ledger plate respectively on opposite sides of the rod. The best constructions further include mechanism for revolving said blade in timed relation to the movement of said frame. The various means referred to may be widely varied in construction within the scope of the claims, for the particular device selected to illustrate the invention is but one of many possible concrete embodiments of the same. The invention therefore is not to be restricted to the precise details of the structure shown and described.

Referring now to the drawings, as shown in Fig. 1, the cutoff is driven from the main drive shaft 10 of the cigarette machine through gears 11 and 12 the latter on the vertical drive shaft 13 which is supported by bearings 14 and 15 in a sleeve 16. On the upper end of the shaft 13 is mounted a gear 19 which through a bevel gear 20 drives the horizontal crankshaft 21. The latter is supported by a housing 22 and housing cover 23 in bearings 24 held by a sleeve 25 on the shaft 21.

Flying supports for the knife carrying frame are provided consisting of crank pins 32, 33 and 34 on crankshafts 21, 26 and 27, the latter two shafts being journaled in bearings 28 and 29 held in by sleeves 30 and 31, respectively. Crank pins 32, 33 and 34 by means of bearings 35, 36 and 37, respectively, support the frame 38 for flying movement in a circular orbital path.

The frame 38 together with the cover 39 forms a housing in which the bearings of crank pins 32 and 33 are mounted while in a vertical extension of the frame 38 there is mounted the bearing for the crank pin 34. The bearing 37 is covered by a cap 40.

The frame 38 carries the ledger plate 41 in a downwardly offset portion connecting the crank engaging parts. The same frame 38, on the upright extension thereof which carries bearing 36, and on the extension 42 supports the horizontal and relatively stationary knife shaft 43 on which is rotatably mounted a spiral gear 44 driven from a spiral gear 45 fixedly mounted on the crank pin 32. The spiral gear 44 is integral with a sleeve 46 supported by bearings 47 and carrying an arm 48 mounting the wafer cutoff blade 49. A cover 50 serves as an oil catcher to keep oil off the cigarette rod. The shafts 21, 26 and 27 have counterbalances 51 to balance the weight of the revolving frame 38.

A grinding wheel 52 is held by a bracket 53 which is mounted on an adjustable rod 54 held by a lug 55 slidable in a bracket 56 mounted on top of the housing 22. Adjustment of the lug 55 is accomplished by means of the handwheel 57, the rod 58 which is held by a bracket 56, which rod has its threaded end entering into lug 55. The grinding wheel 52 is protected by a cover 59 hinged on a stud 60, while a cover 61 hinged on stud 62 protects the knife 49. A burr dressing wheel 63 is held by a fork 64 on a rod 65, adjustably mounted in a bracket 66 attached to housing 67 which forms an extension of housing 22. A slot 68 in the cover 61 permits the latter to be opened without interfering with the rod 65. Stationary guide tubes 69 and 70 for the cigarette rod C are held by housing 67. These guides are cut away at an angle on their undersides to provide a fair way for the ledger plate to the rod. An advantage of the above construction is that shorts drop out there instead of being delivered to the collecting mechanism.

What is claimed is:

- 50 1. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod.
- 55 2. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod, said frame supporting said blade and ledger

plate respectively on opposite sides of the rod.

3. In a continuous rod cigarette machine, the combination with a flying frame, of a cutoff blade and cooperating ledger plate both carried by said frame, and means for moving said frame in an orbital path to cause said blade and ledger plate to operate on the rod, said frame including spaced extensions for supporting the blade on one side of the rod and an offset portion connecting said extensions and supporting the ledger plate on the other side of the rod. 70 75

4. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod, said frame supporting said blade and ledger plate respectively on opposite sides of the rod, and means rotating said blade in timed relation to the movement of said frame to 80 85 cut across the rod when the ledger plate is against the same and swing away from the rod when the ledger plate moves away. 90

5. In a continuous rod cigarette machine, the combination with a flying frame, of a cutoff blade and cooperating ledger plate both carried by said frame, and means for moving said frame in an orbital path to cause said blade and ledger plate to operate on the rod, said means including flying supports for said frame engaging the same 95 100 at least three points.

6. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod, said means including cranks supporting said frame. 110

7. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod, said blade being rotatable on said frame and mechanism for revolving said blade in timed relation to the movement of said frame. 115 120

8. In a continuous rod cigarette machine, the combination with a flying frame, of a cutoff blade and cooperating ledger plate both carried by said frame, and means for moving said frame in an orbital path to cause said blade and ledger plate to operate on the rod, said means including flying supports for said frame, and said blade being mounted for revolution on said frame, and 125 130

means operated by said flying supports for revolving said blade.

9. In a continuous rod cigarette machine, the combination with a flying frame, of a cutoff blade and cooperating ledger plate both carried by said frame, and means for moving said frame in an orbital path to cause said blade and ledger plate to operate on the rod, said means including cranks supporting said frame, a shaft carrying said blade mounted for rotation on said frame and a driving connection between the crank pin of one of said cranks and said shaft.

10. In a continuous rod cigarette machine, the combination with a flying frame, of a cutoff blade and cooperating ledger plate both carried by said frame, and means for moving said frame in an orbital path to cause said blade and ledger plate to operate on the rod, said means including cranks supporting said frame, a shaft carrying said blade mounted for rotation on said frame, gear on the crank pin of one of said cranks, and a gear on said shaft meshing with the crank pin gear.

11. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod, said ledger plate having a rod guiding portion of U shaped cross section.

12. In a continuous rod cigarette machine, the combination with a flying frame, of a cutoff blade and cooperating ledger plate both supported by said frame, and means for moving said frame in an orbital path to cause said blade and ledger plate to move in an orbital path to operate on the rod, said ledger plate having an open top channel engaging said rod during cutting only.

13. In a continuous rod cigarette machine, the combination with a movable frame, of a revolving cutoff blade and cooperating ledger plate carried by said frame, the ledger plate being secured on the frame in fixed relation to the center of rotation of the blade, and means for moving said frame to cause said blade and ledger plate to operate on and simultaneously follow the cigarette rod.

In testimony whereof, I have signed my name to this specification.

ROBERT JOHN ALEXANDER CHANDLER.
